INVENTOR

James P. Kelly,

BY

ATTORNEYS.

UNITED STATES PATENT OFFICE.

JAMES P. KELLY, OF NEW YORK, N. Y.

CORD TIP.

1,420,657.

Specification of Letters Patent. Patented June 27, 1922.

Application filed September 2, 1921. Serial No. 497,867.

To all whom it may concern:

Be it known that I, JAMES P. KELLY, a citizen of the United States of America, residing at New York city, New York 5 County, New York, have invented a new and useful Cord Tip, of which the following is a specification.

My invention relates to a tip or device for finishing or protecting the end of a cord or 10 the like.

The main object is to provide a simple but inexpensive construction which may be readily applied to the end of a cord for preventing it from raveling or fraying out.

Another object is to provide a construction which may be removed and re-applied when necessary.

In its preferred form, the invention contemplates the use of an interior toothed or 20 spiked member adapted to be pushed into the end of a cord, and an exterior sleeve adapted to be adjusted or slipped longitudinally of the cord and to embrace the end of the cord surrounding the spikes or teeth.

Figure 1 is a side view of a construction 25 embodying the improvements of my invention.

Fig. 2 is a sectional view thereof.

Fig. 3 shows the parts being applied.

Fig. 4 shows a modification illustrated in 30 my former application #472,429, filed May 25, 1921, from which application this present application is a continuation.

Fig. 5 is a side view of a modified form 35 of an interior clamping member.

Fig. 6 is a sectional view of another modification.

10 indicates a part of the cord, rope, or lacing, which for convenience will be termed 40 a "cord." The inner part of the clamping means has a shank 11 and a head 12. The shank is preferably pointed at the end opposite the head and provided with a plurality of spikes or teeth 13 inclined toward the 45 head so that the shank and teeth or spikes can be readily pushed into the end of the cord, but cannot be pulled out when the parts are assembled. The sleeve 14 is provided with a shoulder 15 normally abutting 50 against the inner face of the head 12. The sleeve may also have an outer flange 16 em-

bracing the head to more securely hold the parts together. The sleeve may be split as at 17 so as to make it resilient at this end and enable it to be more readily assembled 55 on the head. To assemble the parts, the sleeve is first slipped over the end of the cord a sufficient distance to permit the end to project beyond the sleeve. The shank 11 is then pushed into the end of the cord and 60 the sleeve slipped back toward the end until the head 12 snaps into the grip of the yielding flange 16 of the sleeve. To separate the parts, the cord may be bent so that the pointed end of the shank either protrudes 65 through the side of the cord or at any rate may be reached and pushed upon while the sleeve 14 is slipped to the right as viewed in Fig. 2 sufficiently to disengage the head 12.

In the form shown in Fig. 4 the end of the 70 sleeve 20 abuts against the head 12 in one direction.

In the form shown in Fig. 5, the shank of the inner member is formed of two strips 21-21, each of which is provided with teeth 75 and is bowed outwardly so as to exert a yielding pressure toward the inner wall of the sleeve (not shown in this figure).

In the form shown in Fig. 6, the head 22 of the inner member fits outside of the end 80 23 of the sleeve.

It will be seen that all of the forms described consist of simple parts which may be readily made and readily assembled. The inclined spikes or teeth securely hold the 85 parts together against accidental separation, as the harder the pull upon the cord the more securely the teeth become embedded.

I claim:

1. A cord tip comprising an inner member 90 having a pointed shank with inclined spikes and an outer sleeve for embracing the cord around said spikes.

2. A cord tip comprising an inner member 95 having a head and shank with inclined spikes pointed toward the head, and an outer sleeve member for surrounding a cord and adjacent said spikes.

3. A cord tip comprising an inner member 100 having a shank and a head, and a sleeve for embracing the end of the cord around said

shank and having a flanged portion embracing said head.

4. A cord tip comprising an inner member having a shank and a head and an outer sleeve member for surrounding the end of a cord around said shank, said sleeve member having a split end engaging said head.

5. A cord tip comprising an inner member having a shank and a head and an outer sleeve for surrounding the end of a cord around said shank, said shank extending beyond said sleeve at its inner end.

JAMES P. KELLY.
